UNITED STATES PATENT OFFICE

JOSEPH C. KELLY, OF SAND SPRINGS, OKLAHOMA

SNAP-REVOLVING MACHINE

Application filed February 1, 1930. Serial No. 425,159.

My invention relates broadly to the manufacture of glass articles and more particularly to a warming in machine for all kinds of glass ware which may need refinishing or reshaping. It is adaptable for lamp chimneys, lantern globes, tumblers, bottles, jars, etc.

Previous to my invention difficulty has been experienced in obtaining a correct and evenly distributed heat for the several articles. As is well known to those skilled in this art the several glass articles are held by snaps or punties. These snaps are revolvably supported between aligned parallel discs and adjusted so as to maintain the articles in front of the respective finishing holes. The finishing holes are usually formed in a curved wall and hence it is very difficult to align all of the glass articles so that proper heating occurs.

I overcome the above difficulty by placing several banks of supporting devices along radii of the usual circular furnace or "glory hole." These banks, two of which are shown in the accompanying drawing, are mounted on a single frame and driven by a single prime mover. They form a device which is adapted to cooperate with my arrangement of finishing holes in the curved wall. Thus, it will be seen, that the flames and hot gases rush out through the finishing holes exactly in alignment with the articles to be heated. Thus uniform heating prevails.

Furthermore, if desired, one of the wheels or discs of the pair which support the snap, may be rendered slightly eccentric by making it revolve about a sixty-fourth of an inch off center. This causes the snap to move about twice this distance in an upwardly and sidewise direction. Hence, the glass article not only revolves in its bath of heat but also travels in a small orbit which insures equal heating of all of its portions.

Another advantage lies in the fact that the V-construction of my frame allows the operator ready access to any of the snaps.

Other objects of this invention will be set forth in the following description and drawings which illustrate a preferred embodiment of this invention, it being understood

that the above general statement is extended merely to generally explain the same and not to limit it in any manner.

In the drawing

Figure 1 is a plan view of my invention. 55

Figure 2 is a view in cross section taken along the line II-II of Figure 1.

Figure 3 is a view of one of the banks of snap holders looking in the direction of the arrow A of Figure 1. 60

Figure 4 is a side view of the frame which supports the banks or supports for the snaps.

Figure 5 is an enlarged view, looking in the direction of either of the arrows B, of Figure 1, disclosing the cammed disc or wheel which causes the snap and its article to travel in a small orbit. 65

Referring in detail to the drawing, —C— indicates one bank or section of my invention and —D— the opposed one. These banks or sections are supported or consist of, in part, a frame —F— which is recessed out to form an open space —J— which allows the operator access to the several parts. The framework of each bank is similar, the principal difference being that one is left hand and the other right hand. 70

A furnace or "glory hole" —G— has finishing holes —21—, —31—, —41—, and —51—. Shafts —22— and —23— form a revolving unit which is exactly in line with the parallel holes —21— and —31—. Shaft —23— has discs —62— fastened thereto as shown. Shaft —22— has discs or wheels —62— and —63— rigid therewith and aligned with or opposed to discs on shaft —23—. 75

As shown in Figure 5 the disc —63— has a geometrical center —K— and an actual center of revolution —L—. The distance between these centers is —M— and hence the camming action is equal to twice —M—. Thus the snap —S— is lifted a vertical distance —V— and shifted horizontally a distance —H—. 80

Shafts —32— and —33— are parallel to shafts —22— and —23— and have discs —62— rigid therewith as clearly shown in Figure 1. All four of these shafts are revo- 100

lubly mounted in brackets —64—. Snaps are laid between the discs of each of these units and the drive shafts —23— and —33— rotate them. Rotation is transmitted from shaft —33— to —23— by means of pinion or sprocket wheels —66— and —67— and chain —68—.

A shaft —70—, mounted in brackets —71—, has a bevel gear —72—, which meshes with the bevel gear —73— to drive the shaft —33—. The shaft —70— is rotated by means of a gear —74—, thereon, meshing with a bevel gear —75— on the shaft —42—.

Shafts —42— and —43—, with discs —62— juxtaposed, rotatably mounted in brackets —64— (not shown), form another unit for revolving a snap. The snap —S— is shown in dotted lines. Note that the snap —S— is directly in line with the finishing hole —41—. A gear —76— is connected to any suitable prime mover, not shown, to motivate the several units, and sprockets —77— and —78—, interconnected by chain —79—, drive shafts —42— and —52— in synchronism.

Shaft —53— cooperates with shaft —52— to form the last unit. Shaft —53— has an off center disc —63—, similar to shaft —22—, which causes the article —T— to travel in an orbit.

Figure 2 shows the chain connection between shafts —42— and —52—. Also, chain —80— leads to any suitable prime mover. Figure 3 shows small arrows —X— which indicate the direction of rotation of the discs.

The operation is readily understood. The articles to be heated are simply placed in the snaps and then laid between the proper discs. The snap rolls between the discs and consequently does not sag or flow downwardly. Moreover, it is heated evenly. In the case of the outer snaps slight orbits are caused by the eccentric discs. This makes for even better heating.

What I claim is:

1. A snap revolving machine for an ar-
cuate glass furnace consisting of two banks
of units; means for supporting each bank ra-
dially with respect to the furnace; each bank
consisting of two parallel units; each unit
consisting of two parallel shafts, one a driven
shaft; opposed discs on the last mentioned
two parallel shafts; brackets to revolvably
support all of the shafts; and means to ro-
tate the driven shafts.

2. A snap revolving machine consisting of
a set of two shafts, means for revolvably
mounting the shafts in parallelism, means
for driving one of the shafts, discs near either
end of either shaft fixed thereto; another
identical set of shafts and appurtenances;
and means for maintaining said last men-
tioned set of shafts at an angle to the first
mentioned set.

3. A machine as set forth in claim 2 but

also having the several discs at either end of either set of shafts in alignment.

4. A machine as set forth in claim 2 but
further characterized by the fact that the
means for driving the last mentioned set of
shafts is motivated by the first mentioned re-
volving shaft.

5. A device of the character described hav-
ing several sets of snap revolving mechan-
isms not in alignment; each set comprising
two shafts, means for revolvably mounting the
shafts in parallel relationship; opposed discs
on the two shafts, and means for revolving
one of the shafts.

6. A snap revolving unit comprising two
parallel shafts, brackets for revolvably hold-
ing same in parallel relationship, two discs
on one of the shafts, two discs on the other
shaft in the same plane as the first mentioned
discs, one of said discs being slightly eccen-
tric.

7. In a snap revolving machine having two
parallel shafts with discs thereon the combi-
nation of means to rotate one of the discs
about a pivot slightly distant from its geo-
metrical center.

8. An apparatus of the character described
consisting of a structural V-shaped frame
having two brackets along either side of the
V, shafts mounted in the brackets, discs on
the shafts and means to rotate the shafts in
synchronism.

In testimony whereof I affix my signature.
JOSEPH C. KELLY.
